HUMIDIFIER

Edward S. Cornell, Jr., Larchmont, N. Y., assignor, by mesne assignments, to American Radiator & Standard Sanitary Corporation, New York, N. Y., a corporation of Delaware

Application October 28, 1937, Serial No. 171,538

3 Claims. (Cl. 261—117)

This invention relates to humidifying apparatus and more particularly to an improved humidifying apparatus applicable for the humidification of the atmosphere of a single room or a plurality of rooms.

Characteristics of embodiments of the present invention are singly or plurally as follows: The humidifier assembly embodies components such as the spray element motor and its directly actuated moving parts located as in the basement compartment or like space in a home or in an apartment house, or the like portion of the building usually not traversed by the occupants or their guests, which space may be closed from view, but affording convenience of connection of the spray element with the domestic water supply; convenient connection of the motor usually electric, fan element and associated driving parts, affording also ready inspection and repair when necessary. The assembly also comprises suitable conduit means leading from the spray element to the respective room or rooms served by the humidifier, the assembly, particularly the portion thereof extending to a room being arranged to preclude condensation of the aqueous spray projected by the fan through the conduit.

Amplifying the above stated characteristics, the invention is particularly directed to a humidifier construction embodying a spray element provided with a discharge for unsprayed portions of the water supply to the spray element, combined with means associated with the terminus of the conduit, positively leading liquid aqueous condensation into the conduit, and to the liquid discharge of the spray element thereby preventing the condensation within the room served by the humidifier.

As one form of embodiment of the portion of the conduit extending into the interior of a room and precluding condensation of moisture, the terminus of the conduit, advantageously of artistic configuration, such as rectangular, may be arranged substantially flush with the plaster, plaster board, or like material of the wall of such room, the opening of such terminus being provided with a wire mesh to present a visual sense of closure but affording discharge therethrough of moisture laden air projected by the fan, such wire mesh lying in or extending for a substantial portion thereof at a re-entrant angle with respect to the plane of the terminus, that is to say, lying in or extending from such plane, whereby condensation effected by such wire mesh is positively lead away from the terminus of the conduit and into the conduit, and conveyed

through the conduit to be discharged as through the discharge of the spray element, thereby precluding condensation within the room of moisture furnished by the humidifier.

Further features and objects will be understood from the following detail description and the accompanying drawings in which

Fig. 1 is a side elevation of a preferred embodiment of the invention illustrated in installed relation to a portion of a building, the latter being shown in cross section.

Fig. 2 is a detail sectional view on line 2—2 of Fig. 1.

Fig. 3 is a transverse sectional elevation on line 3—3 of Fig. 2, on a somewhat enlarged scale.

Fig. 4 is an elevation of Fig. 1 as viewed from the right.

Fig. 5 is a detail sectional view, on an enlarged scale, on line 5—5 of Fig. 4.

Fig. 6 is a detail section taken on line 6—6 20 of Fig. 5.

Fig. 7 is a detail sectional view on an enlarged scale, on line 6—6 of Fig. 4.

The preferred embodiment illustrated in the drawings, indicates the same installed in relation to a portion of a building. As illustrated in Figs. 1 and 4, in particular, such installation is shown with relation to the first floor indicated at the floor line 10. A wall or partition of such first floor is indicated at 11. 12—12 indicate supporting joists for the floor 10, in this instance the joist 12 being located in the basement, an advantageous location for the assembly of the water-feeding portion of the embodiment of the invention, including a discharge or drain for superfluous water, as appears more fully herein-after.

Suspended from one or more of the joists 12, but preferably by the arrangement 13 as shown in Figs. 1, 2 and 4, is a bracket 14 which supports 40 a prime mover, such as an electric motor 15, to the driving shaft of which is attached a fan 16. The fan 16 is enclosed within a casing 17, also attached to the bracket 14, and such casing is provided with an opening 18 in the axis of rotation of the fan 16, such opening having a foraminous screen 19, and a baffle plate 20. As appears from Fig. 3, the baffle plate 20 is mounted upon a screw-threaded element to afford adjustment of the plate 20 relative to the opening having the foraminous screen 19, to thereby adjust the effective quantity of air passing through the foraminous screen 19, and thence into the intake opening of the fan 16 and in turn regulate the effective amount of air projected by the fan 16, 55

for any given speed of rotation of its actuating motor, supplied to the humidifying means, referred to more fully hereinafter. The fan casing 17 has its exit end 21 connected to the lower end 5 of a humidifying element 22. This humidifying element 22 comprises a casing and is attached to the bracket 14 in any suitable manner. The upper end of the humidifier casing 22 is open and is connected by an elbow 23 to a horizontal duct 10 24, which is connected in turn by a boot 25 to a vertical duct 26. This vertical duct may be of any suitable length and preferably of such a length to extend to a point slightly above the base-board 27 forming part of the trim of the 15 room of which 10 is the floor. The wall 11 of the room referred to is provided with a horizontally arranged rectangular hole 28, which forms an opening through which extends the discharge elbow 29, such discharge elbow having its inner 20 lower end connected to the upper end of the duct 26. Preferably, the elbow 23 and horizontal duct 24 are circular in cross section, but in order to provide for a sufficient area of opening of the elbow 29 into the room referred to, I may find 25 it desirable to make such elbow substantially rectangular in cross section. Therefore, for convenience of manufacture as well as installation in a restricted space within the confines of the wall 11, as for example where such space is restricted by the studding 30, the duct 26, elbow 29, as well as the boot 25 are substantially rectangular in cross section.

Located within the humidifier chamber 22 and spaced apart from the bottom 31 is a spider 32, 35 this spider being secured in position in any suitable manner, advantageously by means of rivets 33. The spider 32 is centrally bored and threaded to receive an internally and externally threaded annular member 34, the external threads cooperating with the internal threads on the spider 32 and the internal threads cooperating to hold a nipple 35 in position. The nipple 35 at its lower end 36 is reduced in diameter and threaded and extends through a perforation in the bottom 31 40 and is held in fixed position with respect to the bottom by means of the check nut 37.

The nipple 35 is provided with an axial bore 38 therethrough, and the upper or inner end of the nipple is internally threaded to receive the 45 lower threaded end 39 of a spray element or water valve 40. The reduced threaded end 36 is connected by pipe 41 to any suitable source of supply of water or other aqueous material under pressure with an adjustable jet means 42 and by 50 means of which the amount and character of the water spray therefrom may be regulated.

The bottom 31 makes a fluid-tight joint with the lower end of the humidifying chamber 22, and to assist in making such joint, there is a 55 gasket 43 interposed between the lower end of the humidifying chamber 22 and the bottom 31. Extending through the bottom 31 is a drain pipe 44 leading to any suitable waste.

The exit end of the elbow 29 is flanged, as indicated by the reference numeral 45 and the flange is provided with an opening of substantially the same size as the opening in the elbow proper. At each end of the flange are lugs or ears 47, perforated to permit screws 48 to be utilized to position and secure the flange on the wall 11. The opening of the flange 45 is undercut as illustrated in Fig. 5, to assist in holding within the confines of the flange a sheet metal frame 46.

75 The sheet metal frame 46 is provided with a

substantially rectangular opening 49 of a size commensurate with the desired capacity of the humidifying system, and such opening is normally closed by a foraminous sheet 50 of suitable material, such as a screen, and which presents a 5 visual sense of closure but affords discharge therethrough of moisture laden air projected through the ducts 24 and 26. Such screen 50 is attached to the inner face of the sheet metal frame 46 on its upper end and extends inwardly 10 and downwardly therefrom, thus having a substantial portion thereof lying on a re-entrant angle with respect to the plane of the exposed face of such frame. This results in the lower end or edge of such screen extending from the 15 plane in which lies the top of the sheet metal frame 46, rearwardly and downwardly to a point interiorly of the elbow 29, as clearly shown in Fig. 5. The lower edge of the opening 49 is formed of the metal of the frame 46 and is folded 20 to extend inwardly and downwardly, as indicated by the reference numeral 51, and the lower edge of the screen 50 is folded around the exposed edge of the portion 51 and is secured to the under face thereof, as clearly shown in Fig. 5. It will 25 be noted, see Fig. 6, that the portion 51 has cut-away portions 52, 53, etc., which effectually prevent the building up of a quantity of water sufficient to overrun the forward edge of the member 51. Therefore, any moisture condensing on the 30 screen 50 will flow downwardly and be discharged into the elbow 29 and will find its way back through the system of ducts above referred to into the humidifying chamber 22.

The configuration of the flange 45 and the 35 sheet metal frame 46 is advantageously of artistic design, such for example as clearly shown in Fig. 4 and the front or exposed face thereof may be arranged substantially flush with the plasterboard or like forming the wall 11 of the 40 room in which the same is located. The degree of humidification of the room or rooms by use of my improved apparatus, as shown in the drawings, may be controlled manually or by the usual humidistat which in turn controls the operation 45 of the driving motor 15, and should it be desired, the flow of water through the spray element or water valve 40 may be controlled in like manner and simultaneously with the control of the motor 15.

The preferred embodiment of the invention has been shown as a system serving a single room. This showing is for convenience, however, and I may by a proper system of ducts serve a plurality of rooms from a single humidifying unit such as 55 shown in Figs. 1 and 2. This may advantageously be accomplished by utilizing a multi-outlet manifold and at the upper end of the humidifying chamber 22, the various outlets being connected with ducts similar to that illustrated in Fig. 1, 60 for example, and leading to different rooms.

Embodiments of my invention are preferably provided with an electrically operating thermal cut-out, connected electrically in series with the electric motor 15, the temperature responsive 65 element of which cut-out is located on the exterior of the house or other structure, whereby under certain exterior temperature conditions, the motor-fan assembly is rendered non-operative. Such cut-out means is the subject of a 70 presently co-pending application, bearing Serial No. 183,437, filing date January 5, 1938, and entitled Thermostat.

Whereas I have described my invention by reference to specific forms thereof, it will be under- 75

stood that many changes and modifications may be made without departing from the spirit of the invention.

I claim:

- 5 1. Humidifying apparatus for a room or other space of a building, comprising outlet means communicating with the interior of such space, conduit means terminating at said outlet means, said conduit means including a vertically extending portion, said outlet means including foraminous screen means re-entrantly inclined to the vertical in a direction toward the interior of said conduit means, said re-entrantly inclined to the vertical foraminous screen means being disposed 10 within the zone of said outlet means substantially immediately adjacent the interior of the room or other space of the building, water spray means disposed in the vertically extending portion of said conduit means, said water spray means being disposed below the level of the floor of the room or other space of the building, and means for projecting air through said water spray means, to thereby project air through said conduit means laden with moisture supplied by said water spray 15 means, through said outlet means and into such space, and whereby any condensation of moisture within said conduit means is returned to said water spray means.
- 20 2. Humidifying apparatus for a room or other space of a building, comprising outlet means communicating with the interior of such space, conduit means terminating at said outlet means, said outlet means including foraminous screen means re-entrantly inclined to the vertical in a direction toward the interior of said conduit means, said re-entrantly inclined to the vertical foraminous screen means being disposed 20 within the zone of said outlet means substantially immediately adjacent the interior of the room or other space of the building, said re-entrantly inclined foraminous screen means being disposed at the terminus of said outlet means, water spray 25 means, said water spray means being disposed below the level of the floor of the room or other space of the building, means for projecting moisture laden air through said conduit means, to thereby project air laden with moisture through 30 said outlet means and into such space, and whereby any condensation of moisture at said screen means is returned to said conduit means, and means for regulating the quantity of air effectively projected by said moisture laden air 35 projecting means.

EDWARD S. CORNELL, JR.

in the zone of said outlet means substantially immediately adjacent the interior of the room or other space of the building, water spray means and means for projecting moisture laden air through said conduit means said water spray 5 means being disposed below the level of the floor of the room or other space of the building, to thereby project air laden with moisture through said outlet means and into such space, and whereby any condensation of moisture at said screen 10 means is returned to said conduit means.

3. Humidifying apparatus for a room or other space of a building, comprising outlet means communicating with the interior of such space, conduit means terminating at said outlet means, 15 said outlet means including foraminous screen means re-entrantly inclined to the vertical in a direction toward the exterior of said conduit means, said re-entrantly inclined to the vertical foraminous screen means being disposed within 20 the zone of said outlet means substantially immediately adjacent the interior of the room or other space of the building, said re-entrantly inclined foraminous screen means being disposed at the terminus of said outlet means, water spray 25 means, said water spray means being disposed below the level of the floor of the room or other space of the building, means for projecting moisture laden air through said conduit means, to thereby project air laden with moisture through 30 said outlet means and into such space, and whereby any condensation of moisture at said screen means is returned to said conduit means, and means for regulating the quantity of air effectively projected by said moisture laden air 35 projecting means.
